UNITED STATES PATENT OFFICE.

EVERETT F. TAWNEY, OF WINONA, MINNESOTA.

SOAP-DISPENSING DEVICE.

1,210,231.

Specification of Letters Patent. Patented Dec. 26, 1916.

Application filed August 20, 1914. Serial No. 857,742.

To all whom it may concern:

Be it known that I, EVERETT F. TAWNEY, a citizen of the United States, residing at Winona, in the county of Winona and State 5 of Minnesota, have invented new and useful Improvements in Soap-Dispensing Devices, of which the following is a specification.

This invention relates to soap dispensers, and it has particular reference to a device 10 for dispensing so-called soft soap as distinguished from liquid soap, the latter being in the nature of an easy running fluid, while soft soap is of viscous or gelatinous substance.

15 The principal object of the invention is to produce a device of simple and improved construction whereby a predetermined charge may be delivered at each operation.

With this and other ends in view which 20 will readily appear as the nature of the invention is better understood, the same consists in the improved construction and novel arrangement and combination of parts which will be hereinafter fully described 25 and particularly pointed out in the claims.

In the accompanying drawing has been 30 illustrated a simple and preferred form of the invention, it being, however, understood that no limitation is necessarily made to the precise structural details therein exhibited but that changes, alterations and modifications within the scope of the claims may be resorted to when desired.

In the drawing,—Figure 1 is a vertical 35 sectional view partly in elevation of a dispensing device constructed in accordance with the invention, and showing the operating parts in normal or initial position. Fig. 2 is a sectional detail view showing the 40 operating parts in discharging position. Fig. 3 is a sectional view partly in elevation of the piston or plunger which constitutes a part of the invention.

45 Corresponding parts in the several figures are denoted by like characters of reference.

A cylinder 15 is provided intermediate its 50 ends with an obstructing head or closure 16, said cylinder having also at its inner end a supporting flange 17, whereby it may be 55 attached to the wall of a lavatory or in some other convenient position. The front end of the cylinder is provided with a cap 18 which is threaded thereon and which is axially apertured for the passage of a stem 19 carrying a piston P, said stem being also pro-

vided at its outer end with a button or thumb piece 20. The piston P is provided intermediate its ends with an annular recess 21, the reduced portion formed by said recess being provided with a transverse aperture 22. The inner end of the piston has a recess or socket 23 which communicates with the transverse aperture 22 through a bore 24. A spring 25 situated in the socket 23 abuts on the closure 16 and serves to project 60 the piston in an outward direction. The outer portion of the piston is bisected transversely to form two parts or members 26, 27 which are connected together by a threaded stem 28 and between which there is interposed one or more packing washers 29. The stem 28 is engaged with the outer end of the bore 24 which is threaded for the reception of said stem, and the outer end of which is thereby obstructed. 70

The cylinder 15 supports a hopper or container 30 which has been shown as being provided with a nipple 31 that is threaded into the upper portion of the wall of the cylinder. The cylinder is also provided with 80 a downwardly extending discharge nipple 32, the latter being out of alignment with the nipple 31, said discharge nipple being positioned relatively near the outer end of the cylinder. 85

It will be observed that the washer 29 will snugly engage the inner wall of the cylinder, constituting a packing member whereby, when the piston moves in an outward direction, suction is set up in the rearward end 90 of the cylinder, creating a partial vacuum whereby a portion of the viscous or pasty soap substance placed in the container 30 will be positively sucked or drawn through the nipple 31 which constitutes the inlet 95 port into the cylinder. It will also be observed that the parts are so proportioned that when the piston is forced inward against the tension of the spring 23 to the limit of its movement, it will practically 100 abut on the member 16 which constitutes the inner end or head of the cylinder, while when the piston moves outward under the tension of the spring, its inner end portion will partly overlap the inlet port formed 105 by the nipple 31, the extent of the overlap being governed by the number or the thickness of the washers 29. It follows that when the piston is forced outward, the amount of soap entering the cylinder to the rearward 110

of the piston will be governed by the extent of the overlap, thus regulating the amount of the charge.

It is to be particularly understood that 5 the present device is not intended or adapted for dispensing what is commonly known as liquid soap; the soap which is specially prepared for use in connection with this device is of such pasty consistency that while 10 amenable to the action of the suction device, it will not of itself flow or gravitate through the port 31. It will also be seen that the extent of the charge is not governed by the length of the stroke of the piston, said stroke 15 being limited by the piston member 27 in one direction and by the button 20 in the other direction. When the piston is projected outwardly, the bore 24, the space formed by the annular recess 21, the transverse aperture 22 and the socket 23 will be 20 filled with soap, while the space of the cylinder to the rearward of the piston will contain only the relatively small quantity of soap required to form a single charge which 25 has been sucked or withdrawn from the container through the port 31 by the forward movement of the piston.

When the parts are assembled, as shown in Fig. 1, and the cylinder is projected to 30 its full extent in an outward direction by the action of the spring 25, the outlet nipple 32 will be obstructed, but communication will be established between the cylinder 15 and the container 30 through the port 35 formed by the nipple 31. By each operation of the piston or plunger (each operation being taken to mean the pushing inward of the piston against the tension of the spring and its subsequent projection in an 40 outward direction by the action of the spring) will cause a portion of the contents of the hopper 30 to be drawn partly by gravity and partly by the suction created by the plunger into the cylinder. After the 45 operation has been repeated a few times the recess or socket 23, as well as the bore 24, the transverse aperture 22 and the annular space 21 will become filled with the soft soap and a charge of soap will be contained in the 50 cylinder to the rearward of the plunger, so that by the next inward movement of the plunger against the tension of the spring, the inlet port being obstructed by the inner portion of the piston, a portion of the soap 55 contained in the socket 23, bore 24, perforation 22 and recess 21 will be projected through the nipple 32 with which the annular recess 21 will be in registry when the piston or plunger is moved in an inward 60 direction. By the subsequent outward movement of the plunger under the tension

of the spring the next charge is drawn into the cylinder to the rearward of the plunger.

It will be seen from the foregoing description that I have produced a soap dispensing device adapted peculiarly for dispensing soft or viscous soap, a predetermined charge at each operation, and in which the working parts are simple and not liable to get out of working order. The soap 70 in itself constitutes a lubricant whereby the parts are maintained in good working condition.

Having thus described the invention, what is claimed as new, is:—

1. In a device of the class described, a cylinder having non-registering inlet and outlet ports, a hollow piston having an annular reduced portion and a transverse passage establishing continuous communication 80 between the reduced portion of the piston and the cylinder, and a spring seated within the piston to normally project the latter, said piston having means to vary its effective length for the purpose of varying the 85 area of the inlet port, as set forth.

2. In a device of the class described, a cylinder having non-registering inlet and outlet ports, a hollow piston having an annular reduced portion and a transverse passage establishing continuous communication 90 between the reduced portion of the piston and the cylinder, and a spring seated within the piston to normally project the latter; the inlet port being partly overlapped 95 by the piston when the latter is in normally projected position, said piston being provided with means whereby the amount of the overlap may be varied.

3. In a device of the class described, a 100 cylinder having non-registering inlet and outlet ports, a hollow piston having an annular reduced portion and a transverse passage establishing continuous communication between the reduced portion of the piston 105 and the cylinder, and a spring seated within the piston to normally project the latter; the inlet port being partly overlapped by the piston when the latter is in normally projected position, said piston being provided with detachable washers, whereby the 110 amount of the overlap may be varied by varying the thickness of the washer, said washer operating to create a suction upon the return stroke of the piston.

In testimony whereof I affix my signature in presence of two witnesses.

EVERETT F. TAWNEY.
